UNITED STATES PATENT OFFICE.

OTIS A. POPHAM, OF HAYTI, MISSOURI, ASSIGNOR OF ONE-FOURTH TO MELVIN G. McELWRATH, OF HAYTI, MISSOURI.

ADJUSTABLE PORTABLE ROUTER.

Application filed June 6, 1927. Serial No. 196,842.

My invention relates to routing machines of a type adapted for cutting away high places or spots from printing plates which might smear or smudge during the process 5 of printing from stereotypes, electrotypes, thin plate, base-high or type-high plates, or for resurfacing the back of such plates and having adjusting means for use in connection with the very thinnest of shell plates 10 to a slight degree more than type-high plates.

A further object is to provide a machine of this character which may be removably placed in position on a regular printer's 15 table or other horizontal surface and having an electric motor operatively attached thereto.

A further object is to provide means for locking the rotating spindle in adjusted position.

Other objects and advantages reside in the special construction, combination and arrangement of parts forming the invention as more fully hereinafter described and 25 claimed, reference being had to the accompanying drawings forming part hereof, wherein:

Figure 1 is a side elevation view,

Figure 2 is a top plan view,

Figure 3 is a front end view,

Figure 4 is a fragmentary vertical sectional view through the spindle mounting.

Referring to the drawing I have shown my invention comprising a base 5 adapted 35 to be mounted on top of a printer's saw table or other horizontal surface and upon end of which is arranged an angular supporting arm 6 secured to the base by bolts 7 or the like. A pin 8 is arranged in one 40 side of the lower portion of the arm 6 upon which is pivotally mounted an angular motor supporting bracket 9, the bracket extending downwardly over the end of the base and having its end formed into a horizontally 45 arranged table 10 upon which the motor 11 is suitably secured.

The opposite end of the supporting arm 6 is elevated above the base 5 and secured in spaced relation therefrom and comprises 50 a substantially forked shaped end having a bore extending vertically through the arms thereof and fitted with suitable bushings 12 having machine screws 13 extending through the arm of the fork-shaped end and

engaging the bushings whereby to retain the 55 same in position therein. A spindle 14 is rotatably mounted within the bushings having its lower end provided with a chuck 15 adapted to removably carry a pin 16 or the like extending downwardly therefrom. Upon 60 the spindle intermediate its ends and arranged between the arm of the forked-shaped end I provide a pulley wheel 17 secured on the spindle for rotation therewith by a screw 18 extending therethrough and 65 engaging the slot 19 formed vertically in one face of the spindle. It will be observed that while the pulley is secured on the spindle for rotation therewith at the same time the spindle may be moved vertically 70 with respect to the pulley by reason of the slot 19.

An annular groove 20 is formed in the upper end of the spindle and a similar groove 21 is arranged near the lower end thereof. 75 Within these grooves is arranged the yoked ends 22 of a retaining plate 23, the intermediate portion of the plate 23 being vertically arranged in parallel relation with respect to the spindle and the ends 22 thereof being horizontally arranged and extending in a direction toward said spindle. The plate 23 is slidably arranged within guides 24 arranged at the outer edges of the elevated end of the supporting arm 6, one edge 80 of said plate being provided with a rack 25 engaging a gear 26 carried on a shaft 27 having one end thereof rotatably retained in a bracket 28 secured to the end of the supporting arm and its outer end provided 85 with an operating handle 29. It is thus apparent that the retaining plate 23 may be moved vertically by reasons of the rack and gear engagement and since the ends of the retaining plate engage the spindle 14 the 90 same will also be moved therewith. Means for locking the retaining plate in adjusted position is provided, comprising a vertically arranged slot 30 formed in the plate within which is inserted a screw 31 extending from the end of the supporting arm and having a wing nut 32 by means of which the plate 95 may be adjustably secured in position against the end of the supporting arm.

An endless belt 33 may be provided for 100 operating the pulley 17 and the spindle 14, the belt being arranged about a pair of pulleys 34 rotatably mounted on the rear end of

the supporting arm 6 and downwardly about a pulley 35 formed on one end of the shaft of the motor 11. A belt tightener device is provided comprising a screw 36 inserted 5 through an opening within the angular bracket 9 and seated within the lower portion of the supporting arm 6. The angular bracket 9 being pivotally mounted upon the pin 8 is adapted to be moved vertically and 10 by securing the same in proper position by the screw 36 the proper tension may be placed upon the belt 33.

An opening 37 may be drilled in the base 5 in vertical alinement with the pin 16 15 whereby to safeguard the pin from injury should the same pass entirely through the work.

From the foregoing explanation it is believed that the manner of operation of the 20 device as well as the advantages derived through its use will become apparent.

It is obvious that the invention is susceptible to various changes and modifications without departing from the spirit thereof or 25 the scope of the appended claim and I accordingly claim all such forms of the device to which I am entitled.

I claim:

A portable router comprising a spindle support having an elevated end, a rotatably 30 carried vertically disposed spindle at the elevated end of said support and adapted to have a chuck secured at its lower end and formed with a pair of annular grooves adjacent each end thereof, and a vertically extending groove intermediate its ends, a pulley arranged on said spindle having a retaining screw inserted therethrough with its inner end slidably carried in the vertical groove and securing the pulley and spindle 40 for rotating movement, a drive belt for the pulley, a U-shaped retaining plate adjustably secured on the elevated end of the support, with its ends disposed horizontally and arranged in the grooves at the opposite ends 45 of said spindle, a rack formed on one edge of the plate, a gear mounted on the support engageable with the rack whereby to vertically adjust the plate, and means connecting the plate with the support for securing the former in vertically adjusted position.

In testimony whereof I affix my signature.

OTIS A. POPHAM.
